UNITED STATES PATENT OFFICE.

GEORGE H. BLACK, OF ROCHESTER, NEW YORK, ASSIGNOR, BY MESNE ASSIGNMENTS, TO UNITED SHOE MACHINERY CORPORATION, OF PATERSON, NEW JERSEY, A CORPORATION OF NEW JERSEY.

INSOLE AND THE METHOD OF MAKING THE SAME.

1,392,906.

Specification of Letters Patent. Patented Oct. 11, 1921.

Application filed November 10, 1917, Serial No. 201,373. Renewed March 2, 1921. Serial No. 449,239.

To all whom it may concern:

Be it known that I, GEORGE H. BLACK, a citizen of the United States, residing at Rochester, in the county of Monroe and 5 State of New York, have invented certain Improvements in Insoles and the Method of Making the Same, of which the following description, in connection with the accompanying drawings, is a specification, like 10 reference characters on the drawings indicating like parts in the several figures.

This invention relates to the manufacture of shoes and has for its primary objects to improve shoes having pointed or peaked toes 15 and to facilitate the manufacture thereof.

As herein illustrated, the invention is particularly adapted for use in the manufacture of welt shoes although, in certain aspects, it is not limited thereto.

20 In making pointed toe shoes such as are worn largely by women, the major part of the crippling or damaging of the shoes during the inseaming operation results from the pulling away of the sewing rib at the 25 toe from the body of the insole or sole, and particularly at the left side of the end of the toe. This is due to the extreme difficulty experienced in channeling a pointed toe without allowing the knives to cut into the 30 between-substance as the toe is turned in the channeling machine. Such cutting-in weakens the connection of the sewing rib to the body of the insole at a portion of the insole where the inseam stitches are the 35 closest together and where more than the ordinary strains are applied to the stitches while sewing around a narrow toe.

I have by this invention succeeded in so dealing with these and other difficulties as 40 to eliminate substantially all cobbling of the toes after inseaming and to eliminate the evil of pointed toe shoes being returned for ripping at the toe.

An important feature of this invention 45 consists in a peaked toe sole of flexible stock having a marginal lip cut from the body of the sole and upturned to form a sewing rib extending around the shank and forepart and formed and arranged for securing upper 50 materials thereto, and a fabric element secured to the sole, said element terminating forwardly of the ball line of the sole and lying against the sewing rib around the toe from one side to the other to reinforce the

sewing rib at the toe end of the sole. The 55 invention, as herein illustrated by way of exemplification, comprises a reinforced welt shoe insole having a sewing rib and comprising a leather body channeled to produce a lip which is turned up to comprise a 60 part of the sewing rib, and a fabric reinforcement covering the face of the insole and having its marginal portions included in the sewing rib, and a lip strengthening 65 element or reinforce consisting of a triangular piece of material possessing tensile strength and having two upturned edges of substantially the same height as the lip, said strengthening piece terminating approximately at the tip line of the insole being adhesively connected with the body at the 70 point of the toe inside the channel and having said upturned margins connected directly to the inner face of the channel-lip.

The invention will more fully appear from 75 the following description of the illustrative embodiment thereof shown in the accompanying drawings and will then be particularly pointed out in the claims.

Figure 1 of the drawings shows a welt 80 shoe insole body member channeled and having inner and outer channel lips turned up and stitched together for the production of an Economy type of insole;

Fig. 2 shows the lip strengthening ele- 85 ment;

Fig. 3 shows the lip strengthening ele- 90 ment in place on the insole shown in Fig. 1; and

Fig. 4 shows a usual fabric reinforcement 95 applied to the toe strengthened insole.

The welt shoe insole chosen for illustration, and in which this invention has been used with commercial success, consists of a body portion 2 having inner and outer channels 3 and 4 forming lips of the sewing rib. The narrow portion of stock between the channel cuts, commonly designated "the between substance", forms the connection of 100 said lips to the body of the insole. In channeling around a pointed toe it is practically impossible to turn the insole relatively to the cutting blades without causing one or the other of the cutting blades to dig deeper into the between substance, particularly at the left hand side of the toe, than occurs at other parts of the insole. It is, 105 therefore, a usual condition that the con-

nection between the body of the insole and the upturned lips, which constitute the leather part of the sewing rib, is weaker at and near the point of the toe than elsewhere.

5 In accordance with this invention, I provide a strengthening element 10 in the form of a triangular piece of tough sheet material having substantial tensile strength such, for example, as heavy duck. The strengthening 10 element has two upturned edges 11-11 and is adapted to fit into the toe of the insole at the inner side of the channel lips. The strengthening element is preferably coated with strong adhesive material and is formed 15 by pressure snugly into the point of the toe and caused to adhere firmly to the body of the insole and to the inner face of the channel lips. The turning up of the inside channel lip produces a gutter at the base of the 20 inner face of the channel lips and the strengthening element is firmly pressed into said gutter so as to bring the plane of its top face substantially down to the level of the top face of the feather 6 of the insole 25 outside the lips. The upstanding edges of the strengthening element are fitted or cut flush with the top edge of the channel lips. The strengthening element is thus arranged to take the strain of the inseam stitches 30 which connect the upper and welt to the sewing rib of the insole. The strengthening element covers only the toe portion of the insole, terminating in front of the ball portion of the insole, the flexibility of which is 35 therefore in no degree decreased by the present improvement to the toe portion of the insole. This is of importance because the preservation of the flexibility of the insole, except at the toe, is highly desirable, not 40 only to render the finished shoe easy to walk in, but to insure that the insole will conform to the last bottom when assembled thereon during the process of manufacture. When using good quality insole stock a complete 45 reinforce is not desirable because it stiffens the entire sole unnecessarily, causing an objectionable buckling when tacked on the last, and requires the shoe to be "broken in" by the wearer. Furthermore 50 the insole is in a mull temper when inseamed and a complete reinforce will oppose an effective shaping of the insole to the last by the lasting feature of the sewing operation. A strengthening and stiffening element applied 55 only to the area where it is essential to improving the quality of the insole is, therefore, an important feature of the invention. In a convenient application of the strengthening element 10 to an insole the sewing 60 rib 3, 4 and the strengthening element are gripped and clamped during the manufacture of the insole between a forked outer shaping member, which is formed to lie on the feather 6 of the insole and against 65 the outer wall of the sewing rib, and an

inner shaping member, which is formed on its bottom face to press the strengthening element down into the gutter along the base of the channel lip and outwardly against the inner face of the lip. These shaping 70 members may advantageously be heated to cause them to mold the sewing rib accurately into the desired position and into symmetrical relation to the edge of the insole around the end of the toe. A machine 75 such as above outlined is shown and described in my co-pending application Ser. No. 208,639, filed Dec. 28, 1918. The strengthening element shaped and applied as described, being molded down into the 80 gutter and adhesively attached and hot iron molded to the lip, stiffens the toe of the insole, as is desirable, and renders unnecessary a very common practice heretofore followed 85 of dipping the end portion of a pointed toe welt insole in shellac or other stiffening solution. In making covered insoles such as exemplified by the Economy type of insole the usual reinforcing fabric 16 is applied over the entire face of the insole with its 90 margin shaped up by the well known Economy insole making machines to constitute a part of the sewing rib. The Economy type of insole embodying the present invention in the form herein illustrated therefore has 95 the strengthening element 10 located between the body portion 2 of the insole and the reinforcing fabric 16.

It will be noted that, whether the leather portion of the sole is reinforced by the element 10 alone or by it together with the reinforcement 16, the rib is strengthened and the between substance is thickened at the toe, as compared with the portions thereof in the vicinity of the ball line, for example, thus compensating, in each case, for the weakened condition of the rib at the toe without impairing the flexibility of the sole elsewhere.

Having explained the nature of this invention, I claim as new and desire to secure by Letters Patent of the United States:

1. A welt shoe insole having a leather body channeled to produce inner and outer lips which are turned upwardly against each other to form a sewing rib and to receive the stitches which connect the insole, upper and welt, a fabric reinforcement covering the channeled face of the insole from the heel breast line forwardly and having marginal portions thereof included in the sewing rib, and a lip strengthening element arranged in the toe of the insole between said leather body and said fabric reinforcement and comprising a triangular piece of tough material adhesively connected with the leather body in the point of the toe inside said rib and positioned wholly forward of the ball line and having two upturned portions connected to the inner face of said rib 130

and lying between said rib and said fabric reinforcement.

2. A welt shoe insole comprising a body provided with a channel lip turned up to receive the stitches which connect the insole, upper and welt and a gutter or channel at the base of the lip, a lip strengthening element applied to the toe portion of the insole and having its rear edge terminating in front of the ball thereof, said element consisting of a piece of tough material adhesively connected to the insole and pressed down into said gutter and having a portion thereof adjacent to the lip turned up, and a fabric reinforcement covering the channeled side of the insole and having margin portions thereof adjacent to the lip turned up, said lip and said turned up portions of the strengthening element and of the reinforcement being molded together to produce a sewing rib of predetermined shape.
3. A peaked toe sole of flexible stock having a marginal lip cut from the body of the sole and upturned to form a sewing rib to which the upper materials are to be secured, and a reinforce for the peaked toe portion of the sewing rib adhesively connected to the insole and comprising a layer of tough material extending forwardly from approximately the tip line of the sole to the apex of the angle inside the sewing rib and against the inner face of the rib while leaving the main portion of the sole relatively flexible.
4. A peaked toe sole of flexible stock, having a marginal lip cut from the stock and upturned to form a sewing-rib to which the upper materials are to be secured and a toe reinforcing and stiffening element consisting of a flanged triangular sheet of material possessing tensile strength, the base of which approximates the tip line of the sole and the sides of which lie in the apex of the angle at the inside of the sewing-rib and against the inner face of the sewing-rib, the stiffening effect of the flanged sheet being increased by an adhesive between the sheet and the sole, whereby the flexibility of the sole is not decreased except at the toe.
5. A peaked toe sole of flexible stock having a marginal lip cut from the body of the sole and upturned to form a sewing rib extending around the shank and forepart and formed and arranged for securing upper materials thereto, and a fabric element secured to the sole and having its rear edge terminating forwardly of the ball line of the sole,

said element lying against the sewing rib around the toe from one side to the other to reinforce the sewing rib at the toe end of the sole.

6. A peaked toe sole of flexible stock having a marginal lip cut from the body of the sole and upturned to form a sewing rib extending around the shank and forepart and formed and arranged for securing upper materials thereto, and a fabric element extending around the toe from one side to the other and having its rear edge terminating in front of the ball line, said element being formed and arranged to reinforce the sewing rib at the toe, relatively to portions thereof in the vicinity of the ball line, sufficiently to compensate for the weakened condition of the rib at the toe without impairing the flexibility of the sole in the vicinity of the ball line.

7. A peaked toe sole of flexible stock having a marginal lip cut from the body of the sole and upturned to form a sewing rib extending around the shank and forepart and formed and arranged for securing upper materials thereto, and a fabric element secured to the sole, lying against the sewing rib and formed and arranged to provide a greater thickness of between substance at the toe than in the vicinity of the ball line.

8. That method of reinforcing and stiffening peaked toe soles having a weakened sewing-rib forward of the tip line which comprises adhesively connecting to said weakened sewing-rib a reinforcing layer laid in the angle inside the sewing-rib at the toe end only of the insole, and molding said layer down into the apex of said angle and against the inner face of the sewing-rib to form an angular toe reinforcing and stiffening element.

9. That method of reinforcing a weakened sewing-rib forward of the tip line on peaked toe soles while retaining the flexibility of the sole to the rear of the tip line, which comprises adhesively connecting to said sewing rib a triangular sheet of material having its sides flanged and laid in the triangular space within the sewing-rib forward of the tip line with said flanges against the inner face of the sewing-rib; and hot iron molding said sheet into contact with the sole.

In testimony whereof I have signed my name to this specification.

GEORGE H. BLACK.
